AUTOMATIC BIAS FOR DETECTORS OF
SUPERHETERODYNE RECEIVERS

Stuart W. Seeley, Jackson, Mich., assignor, by
mesne assignments, to Radio Corporation of
America, New York, N. Y., a corporation of
Delaware

Application June 21, 1933, Serial No. 676,814

1 Claim. (Cl. 250—20)

It is well known that if the feed-back coupling and other constants in a superheterodyne oscillator remain constant the voltage applied to the first detector from such oscillator increases with 5 an increase in frequency. It is also well known that for optimum detector sensitivity it is necessary that the bias of such detector be always a certain fixed amount greater than the maximum peak swing of the oscillator energy applied to it.

10 These conditions necessitate either costly measures for maintaining the oscillator applied voltage at constant value or varying the bias of the detector tube as the oscillator potential changes.

I have evolved a very simple method of maintaining the detector bias higher than the peak voltage of the oscillator signal by any desired 15 fixed amount.

One object of the invention is to produce an 20 automatic bias for a detector tube coupled to a superheterodyne oscillator.

Another object of the invention is to produce a bias on an intermediate frequency detector by a resistance drop in the grid circuit of the oscillator whereby the bias on the detector varies directly 25 with the variation of voltage of the oscillator.

Other objects will appear in the following description, reference being had to the drawing in which:

30 The single figure of the drawing illustrates circuit arrangements in which the invention is employed.

Referring to the drawing:

The oscillator 1 has its coil L₁ in the tuned 35 plate circuit 2 coupled to its grid coil 3 by a predetermined mutual inductance M₁ between coils L₁ and 3. The grid coil 3 is connected to the filament lead 4 through a resistance R₁. This resistance has a bypass condenser C₁ to filter out 40 the alternating component of the drop around the resistance. One end of the tuned loop 2 is connected to the plate of tube 1 and the other end is connected to the positive side of a plate supply not shown, the negative of which is connected to ground G. The grid 7 of the first 45 detector tube 8 is coupled through coils 9 and 10 with the tuned loop of the oscillator plate circuit. The coils 9 and 10 are tuned by a variable condenser 11 which may be uncontrolled with the 50 condenser 12 of the oscillator plate circuit, these being constructed so that there will always be a desired difference between the oscillator frequency and the signal frequency feeding into the detector coil 9 through primary 13. The resistance R₂ couples the grid 7 of the detector to

the negative end of resistance R₁ to produce the negative bias on the grid. The plate 15 of the detector is connected to loop 16 tuned at the factory or service station to the intermediate frequency and this tuned loop is coupled to subsequent circuits which form no part of the invention and are not illustrated or described. Condenser C₂ filters out any alternating component passing through the resistance R₂. 5

In operation the signal from coil 13 is fed into 10 coil 9 of the first detector tube so that the voltage is applied between the grid 7 and ground G. The oscillator voltage is induced into coil 10 of this grid circuit so that there is a combination between the voltage of the two frequencies and 15 a voltage of intermediate frequency is produced in a well known way. Due to feed-back between the coils L₁ and 3 in the oscillator circuit rectified current flows in the grid circuit through resistance R₁, the alternating component being shunted 20 through bypass condenser C₁. Since the grid circuit of the detector tube is connected through resistance R₂ to the negative end of the resistance R₁, a negative bias is produced on the grid 7, as desired. If a station of a higher frequency 25 is tuned in by manipulation of the condensers 11 and 12 the voltage applied through the modulator coupling M₁, M₂ increases, necessitating an increase in the grid bias of the detector tube for 30 best operation. Since the voltage introduced in coil 3 is increased, there will be increased current through resistance R₁, which increases the negative bias on the detector tube in the proportion desired to give best operation. It will thus be seen that as the set is operated throughout 35 the desired frequency range the detector grid bias is always maintained at the right value for proper detection of the intermediate frequency produced by the reaction of the oscillator with the incoming signal. 40

It may be stated that good results have been obtained for oscillator frequencies between 725 k. c. to 1675 k. c. with the following values:

M₁=20 microhenries.

M₂=7 microhenries.

L₁=210 microhenries.

R₁=50,000 ohms.

R₂=250,000 ohms.

C₁=.002 microfarads.

C₂=.2 microfarads.

45

50

The above values are given only by way of example and variations of course may be made in practice.

It will be apparent that various modifications 55

may be made without departing from the spirit of my invention.

Having described my invention, what I claim is:

- 5 5 In superheterodyne receiving sets, a vacuum tube oscillator having substantially a constant feed-back coupling tending to vary the oscillator voltage directly with its frequency of oscillations, said oscillator having a control electrode, 10 a cathode and an anode, a resistance in the control electrode-cathode circuit of the oscillator having a D. C. potential drop proportional to the voltage in said circuit, a first-detector tube for

rectifying the beats produced by the oscillator and the signal frequencies, said detector tube having a control electrode, a cathode and an anode, means to connect the control electrode and the cathode of said first detector tube respectively to the negative and positive ends of said resistance to produce a negative bias on the control electrode of the first detector tube varying directly with the voltage of the oscillator whereby the optimum value of negative bias is automatically produced for each frequency of oscillation.
